FLOOR RACK CONSTRUCTION FOR
REFRIGERATOR CARS

Howard E. Osborn, Michigan City, Ind.

Application July 21, 1950, Serial No. 175,217

19 Claims. (Cl. 105—375)

1

This invention relates to improvements in floor rack construction for refrigerator cars and it consists of the matters hereinafter described and more particularly pointed out in the appended claims.

One object of the invention is to provide a floor rack construction which itself functions primarily as the load carrying floor for the car and therefore obviates the necessity of providing a strong floor in the car itself for the support of the rack, as is ordinarily the case.

It is also an object of the invention to provide a floor rack of this kind which is so constructed as to efficiently support the lading at an elevation above the floor of the car in a manner preventing contact with the water and brine that might be flooding the floor.

Another object of the invention is to provide a rack for this purpose which is so constructed as to permit a circulation of air up through the same, and laterally from the sides toward the center of the car and also from end to end thereof, longitudinally of the car.

A further object of the invention is to provide a rack construction which may be readily and thoroughly cleaned and moved into a position permitting a like cleaning of the car floor, as by scraping and flushing.

Also it is an object of the invention to provide a rack construction of this kind, which though relatively light in weight, is strong and rigid to withstand stresses imposed by the lading load and which is simple to construct from prefabricated parts for low cost production.

Furthermore, it is an object of the invention to provide a rack of this kind, of an open work construction and including a marginal frame for engagement upon the floor of the car and upper and lower courses of laterally spaced, structural members that are secured to parts of the marginal frame but elevated above the bottom thereof with the structural members in one course extending at a right angle to those in the other course and whereby said courses of structural members coact with each other and with the frame in affording a great strength for the rack so that it will have a long period of usefulness without requiring service or repair.

Again it is an object of the invention to provide a rack capable of carrying extremely heavy loads without damage and which loads are often in the nature of 5000 lbs. concentrated in areas of the order of 1½" by 7" as imposed by the tires of powered lift trucks used in loading or unloading the cars, whether the lading is or is not

2

of the kind requiring refrigeration while the car is en route.

The above mentioned objects of the invention, as well as others, along with the several advantages thereof will more fully appear as the specification proceeds.

In the drawings:

Fig. 1 is a transverse vertical sectional view through the floor of a refrigerator car, equipped with racks embodying the preferred form of the invention.

Fig. 2 is a top plan view of a refrigerator car floor rack made in accordance with the invention, on a scale enlarged over that of Fig. 1, with certain of the parts of the rack being shown as broken away for better illustrative purposes.

Fig. 3 is an end elevation of the improved rack as viewed from the right hand side of Fig. 2.

Fig. 4 is a side elevation of the improved rack as viewed from the near side of Fig. 2.

Fig. 5 is a transverse vertical sectional view through the rack as taken on the line 5—5 and on a scale enlarged over that of Fig. 2.

Fig. 6 is a longitudinal vertical sectional view through the rack, on the scale of Fig. 5, as taken on the line 6—6 of Fig. 2.

Fig. 7 is a fragmentary horizontal detail view through a part of the rack as taken on the line 7—7 and on a scale enlarged over that of Fig. 5.

Fig. 8 is a perspective view of a part of one of the end supports or girders of the rack on substantially the scale of Fig. 7.

Fig. 9 is a perspective view of a part of one of the side supports or girders of the rack on the scale of Fig. 8.

Fig. 10 is a perspective view of a part of one of the top beams embodied in the rack on the scale of Fig. 9.

Fig. 11 is a perspective view of a part of one of the under beams embodied in the rack on the scale of Fig. 10.

Fig. 12 is a side elevation of a portion of a rack embodying a modified form of the invention.

Fig. 13 is a vertical sectional view as taken on the line 13—13 of Fig. 12, with one of the parts in a changed position.

Referring now in detail to that embodiment of the invention illustrated in Figs. 1 to 11 of the accompanying drawing, the improved rack includes a marginal rectangular frame made up of a pair of counterpart end girder beams 15—15 and a pair of counterpart inner and outer side supports 16—16, all of fabricated sheet metal and operatively attached together at their ends, and 55 which best appear in Figs. 3 and 4 respectively.

The beams 15 determine the width of the frame, which is approximately one-half the width of the floor of the car with which it is to be used. The side supports 16 determine the length of the frame and is considerably shorter than the length of the said floor. Usually a number of racks are disposed along each side of the floor to meet substantially on the center line of the floor of the car.

A fragment of one of the end beams best appears in Fig. 8 and as shown therein said beam, which is fabricated of sheet metal, includes an upright web 17 having inturned top and bottom horizontally disposed flanges 18 and 19 respectively. The top flange is somewhat wider than the bottom flange, which forms the floor engaging base for the beam. Depending from that side of the flange 18 opposite the web 17 is a vertical flange 20 that terminates in a horizontally disposed ledge or lip flange 21, considerably narrower than the flange 18. On the center line of the last-mentioned flange is a number of longitudinally spaced, elongated openings 22 for the passage of air therethrough.

The web 17 of the beam is provided with a plurality of longitudinally spaced, rectangular openings 25 therein defined in part by the spaced posts 26. These posts are narrower than the openings 25 and margins of said posts are turned inwardly as right angled flanges 27-27.

The upper portions of the web, in conjunction with the flanges 18 and 20, impart a downwardly opening channel-like cross section to the beam and this cross section is reinforced against distortion or collapse by a plurality of longitudinally spaced, transversely extending stiffener members 28 composed of channel and Z-bars of a depth approximating that of the flange 20. As best shown in Fig. 3, the top flange of each member 28 engages with and is suitably attached to the underside of the flange 18.

The construction above described provides a relatively light weight beam of great strength, capable of withstanding heavy loads without deflection or warping.

Each side support 16 is fabricated from parts formed structurally of sheet metal and is composed of upper and lower vertically spaced angle bar rails 20-31 and upright, longitudinally spaced posts or columns 32-32. The horizontal flanges 33 of each rail face inwardly and the vertical flanges 34 of both rails face toward each other. Each post or column is constituted by a length of channel iron, with the flanges 35 thereof facing inwardly and with the web 36 thereof engaged against the inside of the vertical flanges 34 and fixed thereto with the ends of said webs and said flanges engaging with the opposed faces of the flanges 33-33 of the rails. In the web of each post or column are openings 37, which together with the spaces between the posts or columns 32 provide a maximum of air passages through the side supports as a whole. The ends of the end and side supports 15-16 meet to provide the corners of the frame and each corner is reinforced by a corner angle 38, as best appears in the upper right hand corner of Fig. 2. Said angles 38 function as corner columns in supporting a load imposed directly thereover as when the wheel of a power lift truck passes over a corner of the rack.

The supports 16 have less height than said end beams 15 and when said beams and supports are in frame forming relation, the flanges 19 and the flanges 33 of the bottom rails 31 are in the same plane and the end portions of the ledges 21 of

each beam 15 rest upon and are attached as by welding to the top surface of the flange 33 of the top rails 30 of said supports.

In connection with the frame above described as composed by the pairs of end beams 15-15 and side supports 16-16, the rack also includes upper and lower courses of laterally spaced structural members 40 and 41 respectively, parts of each of which appear in perspective in Figs. 10 and 11 respectively.

The members 40 of the upper course are each of a channel-like cross section and extend parallel with the end beams 15 and the members of the lower course are each of a Z bar-like cross section and extend parallel with the side supports 16 and therefore at a right angle to said members 40.

Each member 40 includes a top web 42 and depending vertical marginal flanges 43-43, each of which terminates in an outwardly extending ledge 44. This provides for each member 40 a cross section which mates with the cross section of the upper portion of each end beam 15. In the web 42 of each member 40 are longitudinally spaced openings 45 that correspond to the openings 23 in the web 18 of the end beams.

Each member 41 includes an upright web 46 and upper and lower oppositely facing horizontal flanges 47 and 48 respectively and in said web are longitudinally spaced openings 49-49 which afford a circulation of air through said web. In each member 40 are transverse stiffeners 41a secured to the underside of the web 42 of the member, as best appears in Fig. 5. These members 41a are in the form of channel and Z-bars, like the members 28 before mentioned.

Each member 41 has a height less than that of the side supports and there is one of these members for each post 26 of the pair of end supports 40 and at each end of the bottom flange of each member 41 is welded an angle bracket or clip 50.

In the completed rack the vertical flanges 50a of the bracket clips are each engaged with and are welded to the inner face of the posts 26 of both end beams 15. The vertical web of each member 41 is disposed inside of and is welded to one of the flanges 27 of said posts, the upper flanges of all of said members being flush with the like flanges of the upper rails of the side supports. This spaces the bottom flanges 48 of said members 41 in a plane above that of the lower flanges 19 and 33 of the end beams and side supports.

Also the flanges 44 of the members 40 engage upon and are welded to the top flanges 47 of all of the members 41.

Thus the webs 18 of the end beams in connection with the webs 42 of the members 40 constitute laterally spaced tread strips of the rack, which are separated by end and intermediate channels 51, which best appear in Fig. 6. The sides of the end channels are defined by the vertical flanges 20 and 43 respectively and the greater part of the bottoms of said channels are defined by the ledges 21 and 44 of the end beams 15 and the members 40 respectively. The sides of the intermediate channels are defined by the vertical flanges 43 of adjacent members 40 and the greater part of the bottoms of the intermediate channels are formed by the flanges 44 of adjacent members 40.

To even up and make the tread surfaces of the rack a continuous one, when so desired, I may fill each channel 51 with a strip or bar 52, preferably of wood, as best appears in Figs. 12 and 13.

Each filler strip or bar may be pivoted at one end to the adjacent flanges 43—43 by cross pins 53 extending through said flanges into opposite sides of the bar, which pins afford a pivotal connection for said strips or bars. Thus, said bars may be swung from the horizontal position wherein they fill said channels to an upright position shown in Fig. 13 and wherein they open or expose the channels. Thus a continuous floor surface may be provided by the racks for lading. When the filler strips are swung into an upright position, cleaning of the rack is facilitated.

That side of each support 30 that is associated with an adjacent side of a car, when installed therein, is provided with a pair of longitudinally spaced hinge ears 54, as best shown in Figs. 1 and 2.

The manner in which the rack functions primarily as the load carrying floor will be best understood by reference to Fig. 1.

In Fig. 1 is illustrated a transverse sectional view through an insulated wooden floor of a refrigerator car of special construction, along with associated portions of the sides and underframe thereof. In said Fig. 1, 60 is the center sill and 61—61 the side sills.

Directly under the floor racks is the car floor 66 which in turn is supported upon the central stringer 65 and the side stringers 65a. Below the stringers 65 and 65a is sub-floor 62 which extends from side sill to side sill, being supported centrally by the stringer 63 which rests on the center sill and on the stringers 64 which are supported by the side sills.

In vertical alignment with the stringers 65a are stringers 70a which are supported by members 74 carried by the underframe cross bearers 75.

From the foregoing it will be understood that any load imposed upon the floor racks will be transmitted through the stringers mentioned directly to the car underframe, because the inner sides of the racks are in operative alignment with the stringers 63—65 and the outer sides are in operative alignment with the stringers 65a—70a. Because of the rigid character of the floor racks, intermediate supports for them become unnecessary and the floor can be of thinner plank than is conventional in refrigerator car construction. Indeed the floor 66 and sub-floor 62 serve primarily as means of confining the insulation 69 therebetween.

Along each side of the upper flooring are upright hinge lugs 70, to which the hinge ears 54 on the racks are pivotally attached by pins 71, which extend longitudinally of the car, just within the vertical planes of the inner sheathings 68 of the side walls.

In said Fig. 1 the racks are shown in their "down" position, wherein they engage flatwise upon the upper flooring. When it is desired to clean this flooring the racks may be swung upwardly about the pins 71 as an axis into an upright position along each side of the car and this exposes substantially the entire surface of the flooring 66 for cleaning purposes.

The improved rack structure, though light in weight, is strong and rigid and ably resists heavy lading loads without deflection when concentrated in small areas as by the wheel tires of a lift truck used in loading or unloading the car.

Also the improved rack provides a maximum of air circulation therethrough in all directions for a proper cooling or refrigerating of perishable products making up the lading.

Again because of the load carrying character

of the racks and their positioning relative to parts supported by the car underframe the car floor is relieved of the burden of carrying the load and hence can be of thinner construction.

5 I claim as my invention:

1. A floor rack construction for refrigerator cars embodying therein side supports for extending longitudinally of the floor of the car and end supports for extending transversely of said floor, spaced bottom beams parallel with said side supports and secured at their ends to said end supports, and spaced top beams at least certain ones of which extend at an angle to and are engaged upon and are fixed to said side supports and to said bottom beams respectively.

10 2. A floor rack construction for refrigerator cars embodying therein side supports for extending longitudinally of the floor of the car and end supports for extending transversely of said floor, spaced bottom beams parallel with said side supports, attached at their ends to said end supports, and spaced top beams parallel with said end supports and engaged upon and fixed to said side supports and to said bottom beams respectively.

15 3. A floor rack construction for refrigerator cars embodying therein side supports for extending longitudinally of the floor of the car and end supports for extending transversely of said floor, spaced bottom beams parallel with said side supports and attached at their ends to said end supports, and spaced top beams parallel with said end supports and engaged upon and fixed to said side supports and to said bottom beams respectively.

20 30 35 4. A floor rack construction for refrigerator cars embodying therein side supports for extending longitudinally of the floor of the car and end supports for extending transversely of said floor, spaced bottom beams parallel with said side supports and attached at their ends to said end supports, and spaced top beams parallel with said end supports and engaged upon and fixed to said side supports and to said bottom beams respectively, the bottom edges of said side and end supports being disposed in the same common plane and the bottom edges of said bottom beams being disposed in a plane above the first mentioned plane.

spaced beams extending between and attached at their ends to one pair of supports and having horizontal flanges at the top disposed in the plane of the tops of the supports of the other pair of supports, and an upper course of spaced structural members arranged at a right angle to the beams in the lower course and engaged and attached at their mid portions to the flanges thereof and attached at their ends to the top portions of the supports in the other pair thereof.

7. A floor rack construction for refrigerator cars embodying therein pairs of right angled supports attached together at their ends to form a rectangular frame, a lower course of spaced structural members extending between and attached at their ends to one pair of supports and each having a horizontal top flange disposed in the plane of the tops of the other pair of supports, and an upper course of spaced downwardly opening channels having laterally extending bottom flanges engaged on and attached to the flanges of said structural members and to the top surface of the supports in the other pair of supports.

8. A floor rack construction for refrigerator cars embodying therein pairs of right angled supports attached together at their ends to form a rectangular frame, a lower course of spaced structural members extending between and attached at their ends to one pair of supports and each having a horizontal top flange disposed in the plane of the tops of the other pair of supports, and an upper course of spaced downwardly opening channels having laterally extending bottom flanges engaged on and attached to the top flanges of said structural members and to the top surface of said other pair of supports, the supports of said one pair of supports carrying channel portions at the top and having their top surfaces disposed in the plane of the top surfaces of the first mentioned channels.

9. A floor rack construction for refrigerator cars embodying therein pairs of right angled supports attached together at their ends to form a rectangular frame, a lower course of spaced structural members extending between and attached at their ends to one pair of supports and each having a horizontal top flange disposed in the plane of the tops of the other pair of supports, and an upper course of laterally spaced downwardly opening channels having bottom flanges engaged on and attached to the flanges of said structural members and to the top surface of the supports in the other pair of supports, and means disposed within each channel member to stiffen the top portion of the same.

10. A floor rack construction for refrigerator cars embodying therein pairs of right angled supports attached together at their ends to form a rectangular frame, a lower course of spaced structural members extending between and attached at their ends to one pair of supports and each having a horizontal top flange disposed in the plane of the tops of the other pair of supports, and an upper course of spaced downwardly opening channels having laterally extending bottom flanges engaged on and attached to the flanges of said structural members and to the top surface of the other pair of supports, said one pair of supports being formed at the top to provide channel portions having their top surfaces disposed in the plane of the top surfaces of the first mentioned channels.

11. A floor rack construction for refrigerator

cars embodying therein an open rectangular frame comprising pairs of side and end supports attached together at their ends, the supports of one pair including upright webs having openings therein separated by upright post portions, a lower course of spaced structural members arranged parallel with the other pair of supports, means for attaching the ends of said structural members to the posts of said one pair of supports and having their top surfaces disposed in the plane of the top surface of the other pair of supports, and an upper course of spaced structural members arranged parallel with said one pair of supports and engaged and attached to the top surfaces of said first mentioned structural members and the top surface of the other pair of supports.

12. A floor rack construction for refrigerator cars embodying therein an open rectangular frame comprising pairs of side and end supports attached together at their ends, the end supports including upright webs, having openings therein separated by upright post portions, at least one margin of each post being turned inwardly as a flange, a lower course of spaced structural members each including an upright web arranged parallel with the pair of side supports, the ends of the upright web of said structural members being fixed to said flanges of said side supports, and an upper course of spaced structural members arranged parallel with the side supports and engaged upon and attached to the tops of the end supports and to the tops of said structural members in said lower course.

13. A floor rack construction for refrigerator cars embodying therein pairs of right angled supports attached together at their ends to form a rectangular frame, one pair of supports comprising upper and lower angle bars and longitudinally spaced posts connecting said angle bars, a lower course of spaced beams arranged parallel with said pair of supports and attached at their ends to the other pair of supports and having their top surfaces disposed in the plane of the top surfaces of the upper angle bars of the first mentioned pair of supports, and an upper course of structural members arranged parallel with the other pair of supports and engaged upon and attached to the first mentioned pair of supports and to said flanges of said beams.

14. In a floor rack construction for refrigerator cars, a frame embodying therein pairs of side and end supports arranged at right angles to each other, a plurality of courses of beams arranged one above the other and supported from said pairs of supports, and means at the corners of the frame securing the ends of said supports together and each acting as a corner column in supporting a load imposed upon said corners.

15. A refrigerator car comprising an under-frame having side and center sills and cross members extending between the side and center sills, a floor and a load carrying floor rack comprising structure having inner and outer sides supported by the underframe and beams parallel with said inner and outer sides with the bottoms of said beams disposed in a plane above the floor of the car whereby that portion of the floor between the inner and outer sides of the floor rack is primarily relieved of the load imposed upon the floor rack.

16. A refrigerator car comprising an under-frame having side and center sills and cross bearers extending between the sills, a floor, a sub-floor, and longitudinally disposed stringer means spacing said floor and sub-floor apart

vertically and being supported by the car underframe, and a pair of load carrying floor racks extending across the car floor and each having a rectangular outline and an inner side in vertical alignment with one of said stringer means and an outer side in substantial vertical alignment with other of said stringer means whereby the floor portions within said outline are primarily relieved of the load imposed upon said floor racks.

17. A refrigerator car comprising an underframe having side and center sills and cross bearers extending between the sills, a floor, a subfloor, and longitudinally disposed center and side stringers spacing said floor and sub-floor apart vertically, said center stringer being supported by the center sill and the other stringers by other parts of the car underframe, and a load carrying refrigerator rack comprising structure having a rectangular outline and an inner side in vertical alignment with said central stringer and an outer side in substantial vertical alignment with one of said side stringers whereby the floor portions within the outline of said rack are primarily relieved of the load imposed upon the floor rack.

18. A refrigerator car comprising an underframe having side and center sills and cross bearers extending between the sills, a floor, a subfloor, and longitudinally disposed center and side stringers spacing said floor and sub-floor apart vertically, said center stringer being supported by the center sill and the other stringers by other parts of the car underframe, and a pair of load carrying refrigerator racks extending across the car floor and each having a rectangular outline and an inner side in substantial vertical alignment with the stringer supported by the center sill and one rack having an outer side in vertical

alignment with other stringers and the other rack having an outer side in vertical alignment with one of the other stringers, whereby the floor portions within said outline are primarily relieved of the load imposed upon the floor racks.

19. A refrigerator car comprising an underframe having side and center sills and cross bearers extending between the sills, a floor, a subfloor extending between the side sills, and longitudinally disposed center and side stringers spacing said floor and sub-floor apart vertically, said center stringer supported by the center sill and the side stringers by cross bearers of the car underframe, and a load carrying refrigerator rack comprising structure having a rectangular outline and an inner side in substantial vertical alignment with said central stringer and an outer side in vertical alignment with one of said side stringers whereby the floor portions within said outline are primarily relieved of the load imposed upon the floor rack.

HOWARD E. OSBORN.
